Primary Examiner — Michael A. Pratt(74) *Attorney, Agent, or Firm* — Abel Schillinger, LLP; Thomas H. Osborn(57) **CLAIM**

The ornamental design for an attachment piece and whole clip assembly, as shown and described.

DESCRIPTION

FIGS. 1 to 4 are perspective views of other embodiments of the attachment piece and whole clip assembly.

The broken lines in the Figures depict environment and portions of the attachment piece and whole clip assembly that form no part of the claimed design.
